(57) **CLAIM**

The ornamental design for a handbag frame as shown and described.

DESCRIPTION

FIG. 1 is a front perspective view of a handbag frame showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a front perspective view of the handbag frame shown in FIG. 1 in the environment of use of a handbag;

FIG. 9 is a left side view thereof;

FIG. 10 is a right side view thereof;

FIG. 11 is a front view thereof;

FIG. 12 is a back view thereof;

FIG. 13 is a top view thereof;

FIG. 14 is a bottom view thereof;

FIG. 15. is a front perspective view of an alternative embodiment of the handbag frame shown in FIG. 1;

FIG. 16 is a left side view thereof;

FIG. 17 is a right side view thereof;

FIG. 18 is a front view thereof;

FIG. 19 is a back view thereof;

FIG. 20 is a top view thereof;

FIG. 21 is a bottom view thereof;

FIG. 22 is a front perspective view of the handbag frame shown in FIG. 15 in the environment of use of a handbag;

FIG. 23 is a left side view thereof;

FIG. 24 is a right side view thereof;

FIG. 25 is a front view thereof;

FIG. 26 is a back view thereof;

FIG. 27 is a top view thereof; and,

FIG. 28 is a bottom view thereof.

(Continued)

The broken lines in the figures depict portions of the handbag frame that form no part of the claimed design. The broken line showing of a handbag in the figures depicts unclaimed environment.
